ATTORNEY

UNITED STATES PATENT OFFICE.

JOHN F. KELLY, OF TRENTON, NEW JERSEY, ASSIGNOR TO THOMAS MADDOCK'S SONS CO., OF TRENTON, NEW JERSEY, A CORPORATION OF NEW JERSEY.

FAUCET ATTACHMENT FOR LAVATORIES.

1,424,251.

Specification of Letters Patent. Patented Aug. 1, 1922.

Application filed March 29, 1922. Serial No. 547,706.

To all whom it may concern:
Be it known that I, JOHN F. KELLY, a citizen of the United States, residing at the city of Trenton, county of Mercer, State of New Jersey, have invented certain new and useful Improvements in Faucet Attachments for Lavatories; and I do hereby declare the following to be a full, clear, and exact description of the invention, such as will enable others skilled in the art to which it appertains, to make and use the same.

The invention relates to a faucet attachment for lavatories made of earthenware, vitreous china or the like, and has for its object the provision of a block-like element preferably made of the same material as the lavatory proper, having a passageway therethrough terminating in a spout overhanging one end of the block, and a vertical opening therethrough adapted to receive the valve casing, by means of which the block may be secured to the slab of the lavatory, with the spout overhanging the bowl, the valve in the casing controlling the water supply to the attachment, so that the latter delivers the water either into the bowl or into a drinking vessel held in the bowl below the curved spout.

The invention is illustrated in the accompanying drawings, in which,

Fig. 1 is a fragmentary sectional elevation of an earthenware lavatory having one form of the invention applied thereto.

Fig. 2 is a similar view showing a modified form of the invention.

Referring to Fig. 1 of the drawings, 1 indicates the slab of a typical lavatory of this general type, provided with a pendant apron or skirting 2 and an integral bowl 3, which is preferably formed of china, clay or other vitreous material. It has been customary to provide lavatories of this type with fittings and accessories, including the faucets or taps, of metal, the exposed portions of which are liable to corrosion, necessitating frequent polishing, which destroys the metal plating. Furthermore, the plumbing connections to the faucets are more or less complicated and expensive, especially in the case of the separate drinking water faucet, applied to a lavatory.

The present invention is designed to overcome these difficulties and to provide a simple, inexpensive and effective form of faucet attachment, preferably made of the

same material as the lavatory proper, and adapted to be clamped in position on the top of the slab surrounding the lavatory bowl, so that the spout of the faucet attachment will overhang the bowl.

Generally speaking, the body of the faucet attachment comprises a block of earthenware having a passageway therein terminating in a curved spout overhanging one end of the block, so that, when the latter is mounted on the slab of the lavatory, the spout will overhang the bowl. In Fig. 1 of the drawings, 7 indicates the slab or block, which may be either round or generally rectangular in plan, said block having a longitudinal passageway 8 therein and an arculate extension 9 constituting a spout, the outlet opening 10 of which forms the terminus of the passageway 8, and overhangs the end of the block.

Intersecting the passageway 8 is a vertical opening 11, adapted to receive a cylindrical body portion or casing of a valve member, by means of which the attachment is secured to the slab of the lavatory.

The valve comprises a cylindrical casing 12 externally screw-threaded at its upper and lower portions to receive set-nuts and packing washers 14 and 15 on the lower end, and 17 and 18 on the upper end, by means of which the valve is locked in proper relation in registering openings 11 in the block 7 and 11' in the slab 1, and the block 7 is secured to the top of the lavatory slab. An additional packing 42 confined by a set-nut 41, occupies a recess 40 in the bottom of the block 7 surrounding the opening 11.

The valve casing 12 is provided with a perforated partition 19 constituting a valve seat, and with lateral perforations 20 communicating with the passageway or duct 8 in the block 7. The valve disc or button 25 is secured to a stem 26 working through the valve casing and having its upper end suitably screw-threaded to receive a set-nut 27 confining a helical spring 24, which normally seats the valve, and also confines packing washers 22 and 23 in proper position to prevent leakage past the valve stem. Mounted on the upper end of the valve stem is a knob or button 29, the body portion of which is preferably made of the same material as the lavatory and the block 7, and surrounding the upper portion of the valve casing is a hood or housing 28, which may

also be made of the same material as the lavatory and block, and which is secured in position by means of a threaded ring 28' attached to the inner peripheral face of the 5 housing and engaging external screw-threads on the set-nut 17, the parts being so arranged that the lower edge of the housing 28 may be drawn into close contact with the top of the block 7. In this particular form 10 of the invention, it will be noted that when the valve disc 25 is moved out of engagement with the seat 19 by pressing down on the knob 29, the water from the supply pipe will pass through the valve casing, and by 15 openings 20 into the passageway or duct 8, and be discharged at the opening 10 in the spout 9. It will also be noted that the faucet attachment as described may be applied at any desired or convenient position on the 20 slab of the lavatory, with the spout 9 overhanging the bowl, and that when so applied, the attachment will be in strict harmony as to finish and appearance with the other elements of the bowl structure, and 25 may be maintained in strictly sanitary condition, as there are no external pockets, recesses, or sharp angles to accumulate dust, dirt and sediment.

In the modification shown in Fig. 2, the 30 only material variation is the provision of a separate goose-neck pipe for conducting the water to the discharge outlet, within the passageway 8', which latter may be conveniently left open at its bottom to permit 35 the ready application of the valve mechanism and the discharge spout. In this form, the passageway 8' and the spout member 9' are made somewhat larger, but in other respects they correspond as to contour and arrangement with the similar elements in Fig. 40

1. The valve mechanism which, as illustrated, is similar to that employed in Fig. 1, serves to secure the block 7' in proper position on top of the slab 1 so that the discharge end 10' of the spout 9' overhangs 45 the bowl. One end of the goose-neck discharge pipe 30 is connected directly with the valve casing 12, and the other end is locked within the discharge end 10' of the spout by means of a perforated thimble 34 screwed 50 to the end of the pipe 30, and having a marginal flange seated in an annular recess in the discharge end 10' of the spout.

In this particular form of the invention it is not necessary to provide the intermediate packing between the valve casing and the lower portion of the block, for the reason that the water passes directly through the valve casing and into the discharge pipe 30. It will be understood that the particular type of valve illustrated in connection with both forms of the invention is merely typical, and that any other appropriate form of valve provided with the necessary accessories for securing the same to the slab 60 and the block, and preferably securing the latter two elements in proper relation, may be substituted therefor.

What I claim is:

An article of manufacture comprising a 70 block of earthenware having substantially flat parallel top and bottom faces, an arcuate extension at one end and above the plane of the top, a passageway through the block and said arcuate extension, the arcuate extension constituting a curved spout overhanging one end of the block, and a vertical opening to receive a valve casing.

In testimony whereof I affix my signature.

JOHN F. KELLY.
